Patented Dec. 15, 1914.

UNITED STATES PATENT OFFICE.

ALLEN E. OSTRANDER, OF RIDGEWOOD, NEW JERSEY.

CAR END CONSTRUCTION.

1,120,739.

Specification of Letters Patent.

Patented Dec. 15, 1914.

Application filed June 10, 1913. Serial No. 772,908.

To all whom it may concern:

Be it known that I, ALLEN E. OSTRANDER, residing at Ridgewood, Bergen county, New Jersey, and being a citizen of the United States, have invented certain new and useful Improvements in Car End Construction, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is an elevational view of approximately one-half of a wall constructed in accordance with this invention. Fig. 2 is an edge view of the structure shown in Fig. 1, showing the parts in section. Fig. 3 is an edge view, looking from the left of Fig. 1. Fig. 4 is a transverse sectional view, the view being taken approximately on the line 4—4 of Fig. 1. Fig. 5 is a fragmentary edge view or side elevation corresponding to Fig. 3, showing a detailed modification hereinafter more fully described. Fig. 6 is an elevational view of the parts shown in Fig. 5. Fig. 7 is a view in transverse section, as in Fig. 4, showing a slightly modified form of construction. Fig. 8 is a similar view of another modification. Fig. 9 is a view taken in section through a slightly modified form of pressed sheet, illustrating a slightly modified form of arch or corrugation, and Fig. 10 is a sectional view taken through one of the sheets hereinafter described, showing the manner of splicing two contiguous overlapping sheets used to form the arches herein-after more fully described.

The invention consists of a wall structure possessing great strength to resist stresses incident to service, and is particularly adapted for use in car construction, in which the vertical walls of the car require stiffness to resist torsional stresses of service and to

resist impact of shifting loads which may 50 come in contact therewith.

One object of the invention is to provide a wall structure which may be associated with conventional framing members of a structure without change in location or details of form thereof, and which wall may be formed principally of metal with associated non-metallic parts, where required, for special purposes, such non-metallic parts being used as linings or interior finish and 60 supports thereof.

Another object is to provide a structural unit which may be transported and subsequently associated with other parts in a car, or similar structure.

Other objects of the invention are economy of manufacture, lightness and durability, as well as economy in transportation.

Referring to the parts, and particularly to Figs. 1 and 10, it will be noted that the 70 metallic sheets F are pressed into form to provide arches 1—1^a, extending in opposite directions from the vertical median line of the sheet F. Depending on the area of the finished structure, either a single sheet may 75 be used pressed into form, or a plurality of sheets may be employed with overlapping and interlocking portions 2—2^a. It will be observed that approximately one-half of the area, vertically, of the sheets projects outwardly from the median line and one-half inwardly from such line, thereby providing oppositely disposed arches which, referring to the outer sheet of Fig. 1, form the outer 80 surface of the wall.

Secured to the outer sheet F, at convenient intervals, is a companion sheet H, which, like the sheet F, is formed into parallel and approximately rectangular arches, though the arches of the sheet H are disposed vertically, while the arches of the sheets F are disposed horizontally, so that the arches G of sheet F and the arches I of the sheet H cross at frequent intervals, at which crossing points there is a considerable 95 gap or space between such arches, and intermediate the arches there are provided zones B—B of contact of the metal forming

such crossing arches, and in the zones of contact at the edge portions of the sheets the companion sheets are connected together by suitable rivets S, which rivets not only connect the arched sheets together but also secure said sheets in position with reference to structural framing parts, hereinafter identified.

While I prefer to use the arches shown in Figs. 2, 3 and 4, either lapped as shown in Fig. 10 or formed of continuous sheets, it is evident that arches of different contour may be employed, such, for example, as shown in Fig. 9, in which the faces 5 and 6 extend in substantially parallel lines and are connected by obliquely disposed flanges 7, instead of the flanges 8 of the other figures, disposed at approximately right angles to their contacting faces.

If found desirable, the sheets forming the crossing arches may be connected together at intervals by any suitable means, as rivets or by electrical spot welding, as indicated at X, Fig. 1.

Thus far the portion of the wall structure described consists of the substantially conterminous sheets F and H. The sheets F and H will be hereinafter referred to as the arched wall portion, and said arched wall portion is in practice associated with a base sill 10, which in the present instance represents an end sill of a car to which said arched wall portion is secured, preferably against the inner face 11 of the web of such sill, with one of its arches G resting upon the top flange 12 of such end sill, so that the end sill is lapped by the arched wall portion and is adapted to serve as a support therefor while the parts are being connected together by the rivets used for that purpose.

The top plate or rail 13 of the structure in the present instance represents the end plate of a box car, which is provided with a vertical web portion, a relatively horizontal flange 14 at its upper end and a horizontal flange 15 at its lower end, and it is to be noted that the end plate 13 laps the arched wall portion and rests upon the upper horizontal arch G of the outer plate of such wall portion, the parts being connected together by the rivets S, before referred to.

As will be noted in Figs. 1 and 2, the roof structure 16 rests upon and is supported at its ends by said horizontal flange.

In structures entirely formed of metal, continuous angle plates may be provided, extending vertically along the edges of the wall, but as the structure illustrated in the drawing is intended primarily for use as an end wall in box cars, the angle members at the edge comprise spaced straps 20, which, preferably, project over the faces of the

arched wall portion, as best shown in Fig. 1, and are secured thereto by suitable rivets 21, as shown in said Fig. 1 and Fig. 4, said straps 20 extending around and lapping the side wall of the car, which side wall is not shown, and are secured to said side wall.

Instead of the interlocking lap, shown in Fig. 10, the sheets forming the arched wall portion may be flanged, as shown at 23 in Fig. 4, such flanges being connected by suitable rivets, as 24, indicated in Figs. 1 and 4, or, as shown in Figs. 7 and 8, the flanges 23^a may be spaced apart a greater or less distance and one or more nail strips, as 30^a, may be interposed between such flanges 23^a to bind them together upon the insertion of bolts or other suitable fastening means.

At the side edges of the wall and extending vertically thereof and preferably between inwardly extending flanges 25, which flanges may be and are shown as integral with sheet H, the arches G of said sheet 85 tapering near their ends to terminate in said flanges, I provide corner posts 26, which are commonly incident to wood car construction, and to these corner posts and the nail strips 30—30^a is secured the wood lining 90 32 of the car or wall structure.

It will be noted that the angle connection straps 20 are disposed between the outer horizontal arches G in Figs. 1 and 4, but, if desired, these corner angle connection straps 95 may be made wider and be connected by suitable rivet connection with a plurality of such arches G, as shown in Figs. 5 and 6.

To provide a support for the floor nail strip, or for the floor, I prefer to connect to 100 the inner face of the end sills or bottom sills 10 an angle 35, the horizontal leg of which may be positioned to close the bottoms of the arches I of sheet F and projects into the interior of the structure, and on this may 105 rest the floor boards direct, or nail strips may be placed on the angle and the floor boards connected thereto, as may be desired.

Thus it will be evident that the arched wall portion may be assembled as a unit with or without the sill 10 and plate 13, or its equivalent, and shipped as an article of commerce, or it may be associated with such parts and the whole structure transported. In either case a number of units of the wall portion may be crated and shipped to the point of assembly, where they may be assembled for service.

What I claim is:

1. In a car end construction, parallel sheets of metal comprising parallel and crossing arches spaced apart vertically and horizontally, the opposite ends of the horizontally spaced arches tapering and terminating in connection flanges.

2. In a car end construction, an end sill and lapping parallel sheets of metal comprising parallel and crossing arches spaced apart vertically and horizontally, the opposite ends of the horizontally spaced arches tapering and being bent to form connection flanges. 65
3. In a wall construction for railway cars, a plurality of relatively parallel conterminous plates each of which is formed with spaced parallel arches, and with portions intermediate the arches in connected contact, and a top plate parallel to and connected with each of said plates and arranged parallel with some of said arches and at an angle to others of said arches. 70
4. In a vertical wall construction for railway cars, a plurality of relatively parallel plates each of which is formed with spaced parallel arches, and with portions intermediate the arches in connected contact, and a top plate parallel to and lapping a plurality of said arched plates and disposed parallel with the arches of one of said plates and at an angle to the arches of another of said plates. 75
5. In an end construction for railway cars, a plurality of relatively parallel plates each of which is formed with spaced parallel arches, and with portions intermediate the arches in connected contact, and a top plate parallel with some of said arches and at an angle to others of said arches, said top plate being connected to said plates by means connecting the plates. 80
6. In an end construction for railway cars, a plurality of relatively parallel plates each of which is formed with spaced parallel arches, and with portions intermediate the arches in connected contact, and a top plate in the line of projection of some of said arches and secured to said plates by means connecting the plates. 85
7. In a wall for the body portion of railway cars, a couple of plates comprising spaced arches and portions intermediate said arches, said intermediate portions being connected and in contact for substantially one-half of their area and out of contact for substantially one-half their area, said arches of one plate crossing those of the other, and a top plate secured to and lapping both plates, parallel to some of said arches and near the ends of other of said arches. 90
8. In a construction for railway cars, a couple of plates comprising a plurality of spaced arches and portions intermediate said arches, said intermediate portions being connected and in contact for substantially one-half of their area and out of contact for substantially one-half their area, said arches of one plate crossing those of 95
- the other, a top plate secured parallel with some of said arches and near the ends of other of said arches, and a bottom sill near the opposite ends of the last mentioned arches. 100
9. In a construction for railway cars, oppositely disposed conterminous plates formed with a multiplicity of angularly disposed arches, said plates being spaced apart at the intersection of said arches and in connected contact intermediate the arches, said plates lapping and being secured to a bottom sill and a member secured to said sill closing the ends of some of said arches. 105
10. In a wall construction for railway cars, an end sill, a plurality of relatively parallel plates comprising parallel and crossing arches spaced apart vertically and horizontally, said plates lapping said end sill, and an end plate lapped by said arched plates. 110
11. In an end construction for railway cars, the combination comprising a car end plate, a wall portion comprising a plurality of relatively parallel plates parallel to and their upper ends lapping said car end plate, and each of said parallel wall plates being formed with spaced parallel arches and with portions intermediate the arches in connected contact, and an end sill lapped by said arched plates. 115
12. In an end construction for a box car, a car end plate of angular form in cross section, a wall portion comprising oppositely disposed conterminous plates the upper ends of which are parallel and lap said end plate, said plates formed of a multiplicity of angular crossing arches, said plates being spaced apart at the intersection of said arches and in connected contact intermediate the arches, and an end sill on the outer face of said plates. 120
13. In an end construction for a box car, a car end plate of angular form in cross section, oppositely disposed conterminous plates lapping said end plate, said plates formed of a multiplicity of angular crossing arches, said plates being spaced apart at the intersection of said arches and in connected contact intermediate the arches, and an end sill on the outer face of said plates, one of said arches resting on said end sill. 125
14. In an end construction for a box car, a car end plate of angular form in cross section, oppositely disposed conterminous plates lapping said end plate, said plates formed of a multiplicity of angular crossing arches, said plates being spaced apart at the intersection of said arches and in connected contact intermediate the arches, and an end sill on the outer face of said plates, 130

one of said arches contacting with the lower flanged portion of said end plate.

15. In a wall construction, parallel sheets of metal comprising parallel and crossing arches spaced apart vertically and horizontally, nailing strips held in recesses in said wall, and a non-metallic lining secured to said nailing strips.

16. In a car wall construction, a rolled metal sill and vertically disposed parallel sheets of metal lapping said sill and comprising parallel and crossing arches spaced apart vertically and horizontally, said sheets being secured to said sill.

15 17. In a wall construction, a plurality of relatively parallel plates each of which is formed with spaced parallel arches, and with portions intermediate the arches in connected contact, a vertically disposed top plate secured to both of said parallel plates and parallel with some of said arches and at an angle to others of said arches, and a flanged metal sill forming a base member for said wall secured thereto.

25 18. In a wall construction, a plurality of relatively parallel plates formed with spaced parallel arches, and with portions intermediate the arches in connected contact with each other, a vertically disposed top plate secured to both of said plates parallel with the arches of one of said plates and at an angle to the arches of another of said plates, and a base sill lapping and secured to said plates by means connecting said plate.

40 19. In a wall construction, a plurality of relatively parallel plates each of which is formed with spaced parallel arches, and with portions intermediate the arches in connected contact, a top plate parallel with some of said arches and at an angle to others of said arches, said top plate being connected to said plates by means connecting the plates, and a channel-shaped sill lapping the lower ends of the plates.

45 20. In a wall construction, a plurality of relatively parallel plates each of which is formed with spaced parallel arches, and with portions intermediate the arches in connected contact, and a top plate in the line of projection of some of said arches and secured to said plates by means connecting the plates, a base sill secured to the plates, and nailing strips held in recesses formed by the plates.

55 21. In a wall construction, a couple of plates comprising spaced arches and portions intermediate said arches, said intermediate portions being connected and in contact for substantially one-half of their area and out of contact for substantially one-half their area, the said arches of one plate being angularly disposed to those of

the other, a vertically disposed top plate secured parallel with some of said arches and lapping the ends of other of said arches, a bottom sill lapping the opposite ends of said last mentioned arches, and nailing strips extending vertically above said sill in recesses parallel with some of the arches.

22. In a wall construction, an end sill, a plurality of relatively parallel plates comprising parallel and angularly disposed arches spaced apart vertically and horizontally, said plates lapping said end sill, an end plate lapped by said arched plates, and nailing strips held in recesses formed by said plates.

23. In a wall construction, the combination comprising a car end plate, a plurality of relatively parallel plates lapping said end plate, each of said parallel plates being formed with spaced parallel arches and with portions intermediate the arches in connected contact, a base sill lapped by said arched plates, wood nailing strips held in recesses formed by said arched plates, and a lining secured to said nailing strips.

24. In a wall construction, a vertically disposed upper plate of Z-form in cross section, oppositely disposed conterminous plates lapping said plate, said plates formed of a multiplicity of parallel angular arches which are angularly disposed and spaced apart at the crossing of said arches and in connected contact intermediate the arches, a base sill on the outer face of said plates, nailing strips lapped by some of said plates, and a wood lining secured to said nailing strips.

25. In a box car, a vertically disposed car end plate of angular form in cross section, oppositely disposed conterminous plates lapping said end plate, said latter plates formed of a multiplicity of angular crossing arches and being spaced apart at the crossing of said arches and in connected contact intermediate the arches, and an end sill on the outer face of said plates, one of said arches resting on said end sill, and nailing strips held between flanges of the arched plates.

26. A car wall comprising plates provided with crossing arches, vertical flanges, nailing strips secured to said flanges, and a sheathing secured to the nailing strips.

27. A car wall comprising relatively parallel vertical plates, one of which is provided with vertical arches and vertical flanges and nailing strips held between said flanges, and one of said plates being provided with a plurality of horizontal arches.

28. In a car wall construction, an end sill, a superposed transversely corrugated end sheet, having a corrugation adapted to

rest on said end sill, said sheet being secured to and lapping said end sill.

29. In combination, a vertically disposed plate, formed with parallel vertically disposed arches, a second plate substantially conterminous with said first mentioned plate and formed with horizontally disposed arches, a top rail lapping said vertical arches and extending only to the upper horizontal arch.

30. In combination, a pair of relatively conterminous corrugated plates, one with

its arches extending vertically and one with its arches horizontally disposed, the corrugations extending entirely across each 15 plate, vertical binding members lapping the horizontal arches and extending parallel with the vertical arches.

In witness whereof I have hereunto set my hand in the presence of two witnesses. 20

ALLEN E. OSTRANDER.
